(57) **CLAIM**

The ornamental design for a tread for pneumatic tire, as shown and described.

DESCRIPTION

FIG. 1 is a perspective view of a tread for pneumatic tire incorporating our new design, it being understood that the tread pattern repeats circumferentially throughout the outer circumference;

FIG. 2 is a front elevational view of the tread for pneumatic tire shown in FIG. 1;

FIG. 3 is a rear elevational view of the tread for pneumatic tire;

FIG. 4 is a right side elevational view of the tread for pneumatic tire shown in FIG. 1;

FIG. 5 is a left side elevational view of the tread for pneumatic tire; and,

FIG. 6 is an enlarged front fragmentary view of FIG. 2. The broken line showing of the sidewall and inner bead is included for the purpose of illustrating environment and forms no part of the claimed design.
